Primary Examiner — Cynthia Underwood*(74) Attorney, Agent, or Firm* — Dave Alan Lingbeck(57) **CLAIM**

The ornamental design for a cable identification clip, as shown and described.

DESCRIPTION

FIG. 1 is a rear perspective view of a cable identification clip.

FIG. 2 is side elevation view of the cable identification clip, the opposed side elevation view being a mirror image thereof.

FIG. 3 is a front elevation view of the cable identification clip; and,

FIG. 4 is an end elevation view of the cable identification clip, the opposed end elevation view being a mirror image thereof.

The broken lines represent environment and forms no part of the claim.
